CLAIM

The ornamental design for a vehicle roof mounted fishing rod carrier, as shown and described.

DESCRIPTION

FIG. 1 is a right side/rear perspective view of a vehicle roof mounted fishing rod carrier of my new design, with the access door thereof closed;

FIG. 2 is a top plan view thereof;

FIG. 3 is a left side elevational view thereof;

FIG. 4 is a right side elevational view thereof;

FIG. 5 is a rear elevational view thereof, with the access door thereof closed;

FIG. 6 is a front elevational view thereof;

FIG. 7 is a bottom plan view thereof, showing, *inter alia*, a plurality of threaded mounting holes.

FIG. 8 is a right side elevational view thereof, with a fishing rod disposed therein, it being understood that the fishing rod shown in broken lines is for illustrative purposes only and forms no part of the claimed design; and,

FIG. 9 is a reduced right side elevational view thereof, shown mounted on a vehicle, with the access door thereof closed, and with a fishing rod disposed therein, it being understood that the vehicle, mounting brackets, and fishing rod shown in broken lines are for illustrative purposes only and form no part of the claimed design.
